UNITED STATES PATENT OFFICE.

CLIFTON W. SHERMAN, OF BUFFALO, NEW YORK.

SIDE FRAME FOR CAR-TRUCKS.

1,247,339.

Specification of Letters Patent. Patented Nov. 20, 1917.

Application filed January 16, 1914, Serial No. 812,368. Renewed September 25, 1917. Serial No. 193,193.

To all whom it may concern:

Be it known that I, CLIFTON W. SHERMAN, a citizen of the United States, residing at Buffalo, in the county of Erie and State of New York, have invented new and useful Improvements in Side Frames for Car-Trucks, of which the following is a specification.

In the side frames of trucks such as commonly used for freight cars it has heretofore been customary to connect the upper arch bar with the lower arch bar and tie bar by means of columns arranged on opposite sides of the spring plank and bolster and composed of pillars extending from the upper to the lower bars and vertical tie bolts which operated to connect the arch bars and tie bars with said pillar, said bolts engaging their nuts and bolts against the upper side of the upper arch bar and the underside of the tie bar. This construction has been found objectionable on account of the frequent breakage of the bolts and loosening of the nuts and heads thereof which permitted the central part of the arch bars and tie rods to sag or drop upon the track under the weight of the load imposed upon the same and thereby not only damage the roadway and wreck the cars but also frequently result in the loss of life.

It is the object of this invention to provide improved means for connecting the upper and lower arch bars and the tie bar or similar longitudinal bars so as to eliminate the use of vertical tie bolts and to so construct these connecting means that the possibility of breakage of this connection is practically avoided, thereby insuring greater security in the transportation of freight and also avoiding the loss of rolling stock which has heretofore been occasioned by the breakage of the vertical tie bolts. This desirable improvement is obtained in the present invention mainly by combining the advantages of arch bars with yoke-shaped columns constructed principally of cast steel which not only insure greater economy but also increased safety.

In the accompanying drawings:

Figure 1 is a fragmentary side elevation, partly in section, of a side frame for car trucks embodying one form of my improvements and showing the same adapted more particularly for use on trucks having a com-

paratively long wheel base. Fig. 2 is a top plan view of the same. Fig. 3 is a fragmentary horizontal section, on an enlarged scale, taken in line 3—3, Fig. 1. Figs. 4 and 5 are vertical transverse sections, on an enlarged scale, taken in the correspondingly numbered lines in Fig. 1. Fig. 6 is a fragmentary side elevation, partly in section, of a side frame for car trucks containing another form of my invention and adapted more particularly for use on car trucks having a comparatively short wheel base. Fig. 7 is a fragmentary horizontal section, on a reduced scale, taken in line 7—7, Fig. 6. Figs. 8 and 9 are vertical sections in the correspondingly numbered lines in Fig. 6. Fig. 10 is a fragmentary vertical longitudinal section taken in line 10—10, Fig. 10. Fig. 11 is a fragmentary vertical transverse section taken in line 11—11, Fig. 12. Fig. 12 is a sectional side view of the same and showing another modification of my invention. Fig. 13 is a fragmentary vertical longitudinal section of a car truck side frame showing a further modification of my invention. Fig. 14 is a vertical transverse section of the same taken in line 14—14, Fig. 13. Fig. 15 is a fragmentary vertical longitudinal section of a car truck side frame showing still another form of my invention. Fig. 16 is a vertical transverse section taken in line 16—16, Fig. 15.

Similar characters of reference indicate corresponding parts throughout the several views.

Referring to Figs. 1 to 5, 1 represents the upper longitudinal arch bar, 2 the lower longitudinal arch bar arranged below the upper bar, 3 the longitudinal tie bar arranged below the lower arch bar, 4 the journal boxes which are mounted at opposite ends of the upper and lower arch bars and tie bar, 5 the axles journaled in the journal boxes and 6 the wheels mounted on the axles. The inner or opposing sides of the wheels are engaged by the brake shoes 7 which are mounted on transverse brake beams 8. Above the central part of the lower arch bar is arranged the spring plank which in the present construction is made in the form of a channel bar having its web 9 arranged horizontally and its flanges 10 projecting upwardly. Upon this plank the lower ends of a cluster of springs 11 are mounted pref-

erably by means of a wooden block 12 interposed between these ends of these springs and the upper side of the spring plank. Below the central part of the upper arch bar 5 is arranged the bolster 13 which supports the body of the car and which is supported upon the upper ends of the springs 11, preferably by means of a wooden block 14 interposed between the underside of the bolster and the 10 last mentioned ends of these springs. The parts just described are of the usual and well known construction and have been in common use in side frames for car trucks of this character.

15 In carrying out my invention for use in car trucks having a comparatively long wheel base, as shown in the construction represented in Figs. 1 and 2, it is preferable to employ two inner upright columns 15, 15 which are arranged on opposite sides of the spring plank and bolster and connected with the upper and lower arch bar and tie bar as well as with the spring plank and serve as a guide for the bolster, and two outer columns 16, 16 which connect the upper and lower arch bars and the tie bar and serve as a support for the brake beams.

20 In the construction shown in Figs. 1 to 5, each of the inner columns 15 comprises an 25 upright yoke-shaped pillar 17 preferably constructed of cast steel and provided in its upper part with a vertical slot 180 which opens in the direction of the length of the side frame and in its lower end with a notch 30 or recess 80 which opens downwardly and forms a downwardly facing seat 801 at the upper end of this recess.

30 The lower arch bar 2 is arranged in the recesses 80 and bears with its upper side 40 against the seat 801 at the upper end of this recess and the tie bar 3 is also arranged in this recess and engages its upper side with the underside of the lower arch bar. The lower arch bar and tie bar are securely held 45 against longitudinal displacement in this recess of the pillar 15 by a vertical locking pin 81 projecting downwardly from the top of the recess 80 through corresponding vertical openings 32, 33 in the tie bar and lower 50 arch bar, and these last mentioned bars are confined in said recess and in engagement with said locking pin 81 by a key 82 passing transversely and horizontally through corresponding openings in the walls of said recess so as to engage the underside of the tie bar and provided at one end with a head 83 engaging with the outer side of one wall of the recess and having a cotter pin 84 in its other end which engages with the outer side 55 of the other recess wall. By this means the lower arch bar and the tie bar may be readily attached to or detached from the pillar for convenience in manufacture or making inspection or repairs. The web of the spring 60 plank engages its underside with the upper 65

side of the lower arch bar. The spring plank may be held in place by any suitable means, for instance by securing its vertical flanges 10 by rivets 440 or otherwise to lugs 430 projecting laterally from the inner and outer sides of the lower parts of the inner pillars 15, as shown in Figs. 1, 2, 3 and 5. The upper arch bar passes through the upper part of the slot 180 of each pillar 15 and engages its upper side with the upper seat 181 of this slot. The upper arch bar and each of the inner pillars 15 may be securely held in place relatively to each other by various means, those shown in Figs. 1 to 5 being suitable and comprising a locking 70 wear block 590 arranged in the upper part of the slot 180 and provided with a locking pin 580 preferably formed integrally therewith and projecting upwardly from the upper end thereof through an opening 210 75 formed in the adjacent part of the upper arch bar and into a recess or socket 220 formed in the upper seat 181 of the pillar 15. The locking block may be held in its proper place within the slot 180 of the pillar 15 by 80 various means such as transverse locking pins 630 passing horizontally through coinciding openings in the lower part of this locking block and the adjacent parts of the pillar 15 and engaging the head 631 at its inner end against the inner side of said pillar and the opposite end of this locking pin is 85 provided with a cotter 632 adjacent to the outerside of said pillar. A very simple, strong and durable connection between each 90 inner pillar and the upper bar is thus produced which holds these parts reliably in place so that they will not give way under the heaviest strains to which they are liable to be subjected in use.

95 In the construction shown in Figs. 1 to 5, the bolster is guided in its vertical movements by means of guide lugs 660 arranged on its opposite vertical sides and forming 100 between the same a guideway which receives the opposing vertical guide portions 670 on the companion locking blocks 590. When it is desired to remove the bolster 13 the locking pins 630 are first removed which permits the locking wear blocks 590 to be dropped 105 out of engagement from the upper arch bar and the adjacent parts of the pillars and then moved lengthwise of the side frame to clear the lugs 660 after which the bolster 110 may be moved sidewise from between the adjacent columns without dropping the bolster and without disturbing the cluster of 115 springs 11. The bolster may be again replaced by assembling the parts mentioned 120 reversely to the order just described. The wear due to the vertical motion of the bolster while in use is taken principally by the locking wear blocks 590 and as these can be 125 easily renewed it is possible to keep the truck 130 always in good condition.

Each of the outer or end columns 16 comprises an upright yoke-shaped pillar 160 provided in its upper part with a vertical slot 161 the upper end of which forms a 5 downwardly facing upper seat 182, while its lower part is provided with a recess 800 which opens downwardly through the lower end of the pillar and forms a downwardly facing seat 802 at the upper end of said recess. The lower arch bar and tie are arranged in the recess 800 and the upper side of the tie bar engages with the seat 802 while the underside of the tie bar is engaged by a horizontal key 820 passing transversely 15 through corresponding openings in the walls of the recess 800 and having a head 830 at one of its ends bearing against the outer side of one of these walls, and a cotter pin 840 in its other end bearing against the outer 20 side of the other of these walls, as shown in Figs. 1 and 4. Each of the pillars 160 is provided with a locking pin 310 projecting downwardly from its lower seat 802 through corresponding openings 330, 320 in the lower 25 arch bar and tie bar, as shown in Figs. 1 and 4, thereby holding these parts against longitudinal movement relatively to each other. The upper arch bar passes through the vertical slot of each end pillar and is 30 held with its upper side in engagement with the upper seat 182 by means of a transverse key or pin 183, preferably having the form of a wedge, as shown in Fig. 4, and passing through openings in the adjacent part of the 35 respective end pillar and engaging with the underside of the upper arch bar and having its head 184 arranged outside of one wall of the respective pillar and a cotter pin 185 in its other end arranged outside of the other 40 wall of said pillar. When the parts are assembled the wedge members 183 have their length arranged perpendicular to the plane of the frame and are driven between the upper arch bars and the adjacent portions 45 of the integral column portions for tightening and connecting the same.

By this means the columns are firmly and reliably connected with the longitudinal upper arch bar, lower arch bar and tie bar so 50 as to form a rigid and durable connection with the same which is not liable to give way or become displaced under the severe strains to which the same are subjected while in use, thereby preventing the side 55 frame from dropping and causing accidents such as have frequently occurred in the past when using vertical tie bolts for holding these parts in an assembled position.

It will be apparent that by the use of 60 these columns which are constructed principally of cast steel, triangular truss structures are formed at opposite ends of the side frame, the members of which comprise the outwardly converging ends 100 and 200 of 65 the upper and lower arch bars which are

secured to the tops of the journal boxes 4 and the upright columns 16 connecting the separated parts of these arch bars. Manifestly this structure prevents the lower arch bar from dropping under the load strains 70 and the upper arch bar from being raised by any tendency to draw the journal boxes toward each other, thereby obtaining the greatest benefit of cast steel construction where same is most needed and increasing 75 the safety of the arch bars.

Furthermore, by the use of columns having pillars of yoke form embracing the longitudinal bars of the side frame the constant teetering or vibration of these bars 80 relatively to the columns cannot result in any loosening or breaking of the connection between these bars and the columns as frequently occurs in columns which depend on vertical tie bolts for their connection with 85 the longitudinal bars inasmuch as such bolts tend to loosen slightly under load which permits the arch bars to bend continually while being loaded and unloaded until they finally break.

Aside from the greater security and durability obtained by this construction the parts can be produced at comparatively low cost and can also be readily and easily assembled as well as dismembered for inspection, adjustment or repairs.

When the side frame is of considerable length it is preferable to connect the pillar of each inner column 15 with the pillar of each companion outer column 16 by means 100 of a truss or brace 48 which, as shown in Figs. 1, 2 and 3, may extend from the upper end of each inner pillar to the lower end of each outer pillar and be formed integrally therewith, thereby producing an exceedingly 105 strong structure which is capable of sustaining the greatest loads liable to be imposed upon the same without making the side frame unduly heavy and without materially increasing the cost of the same. In the case 110 of a side frame having a wheel base of moderate length this truss or brace may be omitted and thereby effect a corresponding saving in weight and cost.

For convenience in supporting the brake beams each of the pillars of the outer columns 16 is provided on the inner side of its upper part with a laterally projecting arm 49 to which may be pivotally secured by means of a horizontal transverse pin 50 the 115 hanger 51 which carries at its lower end, the beam of the adjacent brake shoes, as shown in Figs. 1, 2 and 4. The arch bars are preferably so constructed that after the same have been assembled with the columns the 120 corresponding ends 100, 200, thereof are separated slightly, as indicated by dotted lines in Fig. 1, but these are drawn tightly together upon securing the same to the journal boxes, as shown by full lines in the same 125 130

figure. By thus constructing the ends of the arch bars they have to be sprung into final assembled position, the assembling of same is facilitated and the tension of the keys 5 or fastening devices of the adjacent columns is increased, thereby producing a more rigid construction.

When the wheel base of the car truck is comparatively short the outer columns may 10 be omitted and the connection between the upper and lower arch bars and the tie bar may be effected solely by a pair of inner columns, as shown in Figs. 6-10, these columns being constructed as follows:—

- 15 In the construction shown in Figs. 6 to 10, each of the columns comprises an upright pillar 53 preferably constructed of cast steel and provided at its upper end with an opening 18 which receives the upper arch 20 bar 1 and a lower downwardly opening recess 80 which receives the lower arch bar and tie bar. The upper arch bar rests with its underside against the lower side of the upper opening 18 and is interlocked therewith so as 25 to prevent the upper arch bar and the respective inner pillar from moving horizontally lengthwise of the frame one relatively to the other, this being preferably effected by means of a locking pin 20 formed integrally with 30 the pillar and projecting upwardly from the bottom of its upper opening and engaging with an opening 21 formed in the adjacent part of the upper arch bar. These parts are held in an interlocked position by means of 35 a locking block or fastening member 22 which is interposed between the upper side of the arch bar and the top of the upper opening in the pillar. In its preferred form the upper side of the locking block is constructed in the form of a wedge having its upper side 23 inclined lengthwise and engaging with a correspondingly inclined face 24 at the top of the upper opening in the pillar, as shown in Fig. 10, so that upon 40 drawing this locking block lengthwise between the top of the pillar and the top of the upper arch bar until these inclined surfaces engage tightly with each other, the upper arch bar will be pressed firmly down on 45 the bottom of the upper opening in the pillar and securely hold these parts in position relatively to each other. This tightening of the wedge-shaped locking block as well as the holding of the same in position after the 50 parts are assembled may be effected in various ways but preferably by means of a horizontal clamping bolt 25 arranged lengthwise with its shank in opposing longitudinal grooves 26, 27 formed in the top of the 55 upper pillar opening 18 and the upper side of the upper locking block and bearing with its head 28 against one end of the locking block and the adjacent side of the pillar while its nut 29 bears against the other end 60 of the locking block and the adjacent side 65 of the locking block and the adjacent side

of the pillar, as shown in Figs. 6, 8, 9 and 10. Washers 30 are preferably interposed between the head and nut of the clamping bolt 25 and the opposing surfaces of the locking block and pillar.

In the construction shown in Figs. 6 to 9 the lower arch bar and the tie bar are connected with the pillars 53 by the same means which are shown in Figs. 1 and 5 for connecting the lower arch bar and the tie bar 75 with the inner pillars 15 and the same reference characters and description therefore apply to the corresponding parts in these figures.

The lower parts of the pillars of the columns 80 53 are preferably provided with transverse ears 43 to which the flanges 10 of the spring plank may be secured by rivets 44 or otherwise. At each end of the bolster 13 the same is provided on its opposite vertical sides with pairs of guide lugs 45 which form a guideway and which receive between them the adjacent upper opposing salient guide portions 46 of the inner pillars 53, whereby the bolster is guided in its vertical 90 movements on these pillars. When the bolster is made of cast steel these guide lugs are preferably formed integrally with the bolster, as shown in Figs. 1, 3, 6 and 7 but in some of the other types of bolsters these 95 guide lugs are made separate therefrom in the form of blocks and secured thereto in any suitable manner. For the purpose of permitting the bolster to be removed from the side frame without dismembering the 100 latter the inner lower opposing parts of the inner pillars 53 are provided with recesses 47, as shown in Fig. 6, which recesses are of sufficient depth so that upon removing the springs 11 and then lowering the bolster 105 until its guide lugs 45 are arranged in line with these recesses, it is possible to pass the guide lugs of the bolster laterally through the recesses 47 of the inner pillars for the 110 purpose of assembling or dismembering the side frame and bolster.

In this construction of side frame which employs but a single pair of columns the brake hangers 54 are pivotally mounted on arms 55 projecting laterally from the inner 115 upper parts of the pillars 53 of these columns similar to the manner with reference to the outer or end columns shown in Figs. 1, 2 and 4.

In the construction shown in Figs. 11 and 12, the upper arch bar bears against the upper end of a vertical slot 56 formed in the pillar 57 and the opening 21 in the arch bar is engaged by a locking pin 58 formed on the upper side of a locking wear block 120 59 which is secured to the central part of the pillar within its vertical slot 56 in such a manner that this block may be moved vertically therein to permit of assembling or 125 dismembering the parts of side frame or 130

bolster. The pin 58 also engages with a socket 580 in the upper part of the pillar 57 while that side of its lower end opposite the bolster 13 engages with an abutment 581 formed by a transverse brace on the central part of this pillar. After the locking block 59 has been properly assembled with the upper arch bar and the pillar 57 the same may be held in place by various means, for instance, by means of a horizontal fastening pin or rod 60 passing transversely through corresponding openings in the central part of the pillar 57 and the upright locking block 59 and provided with a shoulder 61 bearing against one of the outer walls of the respective pillar and a screw nut 62 bearing against the opposite outer wall of this pillar, as shown in Figs. 11 and 12. This pin may also be provided with an inward extension 63 upon which the upper end of the adjacent brake hanger 64 may be mounted and retained thereon by means of a cotter pin 65 so that this fastening pin serves the double purpose of securing the locking block in place and also supporting the brakes, whereby a separate support for the brake shoes is rendered unnecessary in substantially the same manner as in the construction shown in Figs. 1 to 9. In the construction shown in Figs. 11 and 12, the bolster is guided by means of guide lugs 66 on its opposite vertical sides engaging with the inner opposing vertical guide portions 67 on the vertical locking blocks 59. When it is desired to remove the bolster in this construction this may be accomplished in the same manner as has been already described with reference to the construction shown in Figs. 1 to 5, or this may be effected by first taking out the springs 11 and then dropping the bolster until its guide lugs 66 are below the vertical locking blocks 59 after which the bolster is free to be moved sideways from the side frame through the recesses 68 in the lower parts of the pillars 57. The parts may also be assembled in the same manner. The lower arch bar and the tie bar are secured to the lower ends of the pillars 57 in the same manner as that shown regarding the columns 15 in Figs. 1, 5, 6, 8 and 9 and the same description and reference characters apply to the corresponding parts in the construction shown in Figs. 11 and 12.

In the modification of my invention shown in Figs. 13 and 14 the pillar 40 of the column is provided in its upper part with an upper opening 70 the upper side of which is engaged by the top of the upper arch bar and the latter is interlocked with this pillar by means of a vertical locking pin 71 depending from the top of this opening through the opening in the upper arch bar, and these parts are held in this position by means of a locking wear block 72 ar-

ranged in the upper opening of the pillar 40 and bearing with its upper end against the underside of the top arch bar and with its lower end against the bottom of said upper opening in the pillar. The locking block 72 is retained in proper position on its pillar by means of a horizontal fastening pin 73 passing transversely through corresponding openings in these parts which pin also extends inwardly through openings formed in an arm 74 projecting laterally inward from the upper part of this pillar and serves as a support for the hanger 75 of the adjacent brake beam. The locking block 72 is further interlocked with the pillar 40 by providing its upper end with a notch or recess 76 which receives the lower end of the pin 71 of this pillar, and the lower part of the locking block is provided with a horizontally projecting supporting lug 77 which enters an auxiliary opening 78 formed horizontally in the central part of the pillar 40. In the construction shown in Figs. 13 and 14 the bolster is also guided on the inner part of each locking block 72 by engaging opposite sides of the latter by guide lugs 79 on the bolster. In the construction shown in Figs. 13 and 14 the lower arch bar and tie bar are arranged in a recess or notch 80 which is formed in the lower part of the pillar 40 and opens downwardly from the lower end thereof and the lower arch bar and tie bar are interlocked with this pillar by means of a locking pin 81 depending from the upper side of this recess and engaging with the corresponding openings formed in the lower arch bar and tie bar. The latter are confined in this recess and held firmly in engagement with the upper side thereof and in engagement with the pin 81 by means of a horizontal key 82 engaging with the underside of the tie bar and passing transversely through corresponding openings in the lower members of the bifurcated part of the pillar 40; this key being held in place by engaging the head 83 at one of its ends with one of the outer walls of this pillar and providing its opposite end with a cotter pin 84 which engages the opposite outer wall of the same. This construction has the advantage of convenience for frequent inspection of the same and permitting of readily determining whether or not the side frame is in the proper condition, as well as permitting of readily assembling the parts and dismembering the same for repairs, if necessary.

In the construction shown in Figs. 15 and 16 the lower arch bar and tie bar are connected with the pillar 85 of the column in substantially the same manner as that shown in Figs. 13 and 14. The upper arch bar, however, in the construction shown in Figs. 15 and 16 is secured to this pillar by providing the upper end of the latter with a

recess 86 which opens at the top of this pillar and which is engaged at its bottom by the underside of the upper arch bar. The bottom of this recess is provided with an upwardly projecting pin 87 engaging with the opening 21 in the upper arch bar and the latter is held in said recess and in engagement with said pin 87 by means of a horizontal wedge-shaped key 88 engaging 10 with the upper side of the upper arch bar and passing transversely through corresponding openings in the members of the upper bifurcated portion of this pillar. In the construction shown in Figs. 15 and 16 15 the brake hanger 89 is supported by a horizontal pin 90 passing transversely through the pillar 85 and a laterally projecting arm 91 on the inner side thereof. As shown in Fig. 16, the lower key 82 is constructed in 20 the form of a wedge.

It will be noted that in all of the various constructions which have been shown and described the use of vertical tie bolts for holding the upper and lower arch bars and tie bar together is dispensed with, and that the columns are interlocked with the arch bars and tie bar by so constructing the columns that their pillars embrace the arch bars and tie bar from the outer sides of these 25 bars and are firmly interlocked therewith or tied thereto by mechanical means which will positively prevent these parts from separating or becoming displaced relatively to each other. All liability of the side frame breaking down under the usual strains of loads as has frequently occurred in the past, is by this means avoided, thereby affording greater safety in the use of the cars and also enabling the same to be operated without suffering damage or loss from this cause. 30

I claim as my invention:

1. A side frame for car trucks, comprising a longitudinal bar having an opening, and an upright column comprising a pillar having a seat which receives said bar, a locking pin arranged on said seat and projecting into said opening in said bar from one side thereof, and a fastening member arranged on said pillar and engaging with 45 the opposite side of said bar.

2. A side frame for car trucks, comprising a longitudinal bar provided with a vertical opening, and a column connected with said bar and comprising a pillar having a slot which receives said bar, a locking block arranged in said slot and provided with a locking pin engaging with the opening of said bar and means for securing said block to said pillar. 50

3. A side frame for car trucks, comprising a longitudinal bar provided with a vertical opening, and a column connected with said bar and comprising a pillar having a slot which receives said bar, a locking block

arranged in said slot and provided with a locking pin engaging with the opening of said bar, and a fastening pin passing horizontally through said pillar and block. 65

4. A side frame for car trucks, comprising a longitudinal bar provided with a vertical opening, and a column connected with said bar and comprising a pillar having a slot forming a seat which is engaged by one side of said bar and a socket at the end of the slot, and a locking block arranged in 70 said slot and engaging with the opposite side of said bar and provided with a pin engaging said opening and socket. 75

5. A side frame for car trucks, comprising a longitudinal bar provided with a vertical opening, and a column connected with said bar and comprising a pillar having a slot forming a seat which is engaged by one side of said bar and also provided with an abutment across said slot, and a locking 80 block engaging with said abutment and provided with a pin engaging with said opening of the bar. 85

6. A side frame for car trucks, comprising a longitudinal bar and an integral 90 column made separate from said bar and having parts which embrace said bar and also provided with integral means for supporting a brake mechanism on said column. 95

7. A side frame for car trucks, comprising a longitudinal bar, a column provided with a seat for engaging one side of said bar, a removable block on which a bolster is adapted to be guided and which engages with another side of said bar, and a pin connecting said block and column and adapted to support the brake mechanism of the truck. 100

8. A side frame for car trucks, comprising longitudinal bars, axle bearings arranged at opposite ends of said bars, a pair of inner columns mounted on the central parts of said bars and adapted to receive a bolster between them, and a pair of outer columns mounted on said bars, each outer column being arranged between one of said central columns and one of said bearings. 105

9. A side frame for car trucks, comprising longitudinal bars, axle bearings arranged at opposite ends of said bars, a pair of inner 115 columns mounted on the central parts of said bars and adapted to receive a bolster between them, and a pair of outer columns mounted on said bars, each outer column being arranged between one of said central columns and one of said bearings, and trusses connecting each inner column with the adjacent outer column. 120

10. A side frame for car trucks, comprising upper and lower longitudinal bars, a 125 pair of inner columns connecting the upper and lower bars and adapted to receive a bolster between them, and a pair of outer

columns connecting the upper and lower said columns being independent of said bars.

11. A side frame for car trucks, comprising upper and lower longitudinal bars, and a pair of separate columns connecting said upper and lower bars and provided on their opposing sides with salient portions which are adapted to be engaged by bolster guides 10 while the lower parts of these sides are recessed to permit of passing said bolster guides laterally through the same.

12. A side frame for car trucks, comprising a top arch bar having a vertical opening, a column having a yoke-shaped pillar which embraces said bar and provided with a socket adjacent to said opening, and a locking wear block having a pin engaging said opening of the top arch bar and the 20 companion socket of the pillar.

13. A side frame for car trucks, comprising a top arch bar having a vertical opening, a column having a yoke-shaped pillar which embraces said bar and provided with a socket adjacent to said opening, and a locking wear block having a pin engaging said opening of the top arch bar and the companion socket of the pillar and having a 25 guide portion adapted to be engaged by the 30 guide of a bolster.

14. A side frame for car trucks, comprising a top arch bar having a vertical opening, a column having a yoke-shaped pillar which embraces said bar and provided with a socket adjacent to said opening and with an abutment below said top arch bar, and a locking wear block mounted on the pillar and engaging said abutment and having a 35 pin engaging with the opening of said top arch bar and the socket of said pillar.

15. A side frame for car trucks, comprising a longitudinal bar, and a column com-

prising a pillar having an outwardly opening recess bearing with its inner side against one side of said bar, and a key passing through said pillar and engaging with the opposite side of said bar for confining the latter in said recess. 45

16. A side frame for car trucks, comprising a longitudinal bar provided with a vertical opening, and a column comprising a pillar having a recess extending to an end of the pillar and bearing with its inner side against the inner side of said bar and provided with a pin projecting outwardly into the opening of said bar, and a key passing transversely through said pillar and engaging with the outer side of said bar. 50 55

17. A side frame for car trucks, comprising a longitudinal bar, a column provided with a seat for engaging one side of said bar, a removable block on which a bolster is adapted to be guided and which engages with another side of said bar, and means for connecting said block with said column. 60 65

18. A truck side frame, comprising arch bars, integral column posts connecting the same, and wedge members whose length is perpendicular to the plane of the frame and arranged to tighten and connect said arch 70 bars and column posts.

19. A truck side frame, comprising upper and lower arch bars, integral column posts connecting the same, and wedges driven in between said arch bars and portions of said 75 column posts for tightening and connecting the same.

Witness my hand this 10th day of January, 1914.

CLIFTON W. SHERMAN.
